Primary Examiner — Jeffrey D Asch*Assistant Examiner* — Rebekah A Caruso**(57) CLAIM**

The ornamental design for a cover for an antenna, as shown and described.

DESCRIPTION

FIG. 1 is a bottom, front and left perspective view of a cover for an antenna showing my new design;

FIG. 2 is a bottom plan view thereof;

FIG. 3 is a top plan view thereof;

FIG. 4 is a left side view thereof;

FIG. 5 is a right side view thereof;

FIG. 6 is a front elevational view thereof; and,

FIG. 7 is a rear elevational view thereof.

The broken lines in the drawings illustrate portions of the cover for an antenna which form no part of the claimed design.
